UNITED STATES PATENT OFFICE.

JEPTHA G. HOLLINGSWORTH, OF KANSAS CITY, MISSOURI.

DESIGN FOR A TOILET ARTICLE.

54,741.

Specification for Design.

Patented Mar. 23, 1920.

Application filed September 2, 1919. Serial No. 321,281. Term of patent 14 years.

To all whom it may concern:

Be it known that I, JEPTHA G. HOLLINGSWORTH, a citizen of the United States, and a resident of Kansas City, Jackson county, and State of Missouri, have invented a new, original, and ornamental Design for a Toilet Article, of which the following is a specification, reference being had to the accompanying drawing, forming a part thereof.

In the said drawing:

Figure 1, is a perspective view of a toilet article embodying my new design.

Fig. 2, is a side view of the same.

Fig. 3, is a view of one end of the device.

Fig. 4, is a view of the opposite end of the same.

I claim:

The ornamental design for a toilet article as shown.

JEPTHA G. HOLLINGSWORTH.
